UNITED STATES PATENT OFFICE.

BENJAMIN F. ANTILL, OF SMITH FERRY, PENNSYLVANIA.

SELF-TAPPING SPIGOT.

SPECIFICATION forming part of Letters Patent No. 690,223, dated December 31, 1901.

Application filed October 5, 1900. Serial No. 32,076. (No model.)

To all whom it may concern:

Be it known that I, BENJAMIN F. ANTILL, a citizen of the United States of America, residing at Smith Ferry, in the county of Beaver and State of Pennsylvania, have invented 5 certain new and useful Improvements in Self-Tapping Spigots, of which the following is a specification, reference being had thereto in the accompanying drawings.

10 This invention relates to certain new and useful improvements in self-tapping spigots, and has for its object the provision of novel means whereby a spigot may be easily inserted into a barrel, keg, or cask. 15 The invention has for its further object to bore and ream a bung-hole simultaneously with inserting the spigot, and, furthermore, to provide means whereby a removable handle may be inserted in the spigot in order to 20 obtain sufficient leverage to bore the bung-hole into the head of the barrel.

The invention still further consists in the novel construction, combination, and arrangement of parts to be hereinafter more 25 fully described, and specifically pointed out in the claim.

In describing the invention in detail reference is had to the accompanying drawings, forming a part of this specification, and where- 30 in like numerals of reference indicate corresponding parts throughout the several views, in which—

Figure 1 is a side elevation of my improved spigot, showing the same secured in the head 35 of a barrel, the latter being partly broken away and shown in vertical section. Fig. 2 is a longitudinal sectional view of my improved spigot. Fig. 3 is a top plan view thereof.

40 In the drawings the reference-numeral 1 indicates the barrel, and 2 the head thereof. 3 indicates the spigot, having arranged at its forward end an opening 4, which is adapted to receive a removable handle 5.

45 The reference-numeral 6 indicates a valve, and 7 the screw-threaded tap, the end of said

tap being closed, as shown at 8, and having formed at its sides openings 9. At the end of the tap is rigidly secured an auger 10, adapted to bore the bung-hole into the head 50 of the barrel.

The operation of my improved spigot is as follows: The removable handle is first inserted in the opening 4 and the bit of the auger forced into the head of the barrel, there- 55 by forming a bung-hole, which will be engaged by the screw-threads formed on the tap and then driven home to the desired point.

The many advantages obtained by the use 60 of my improved spigot will be readily apparent, as the operation of boring the bung-hole and inserting the spigot is but a single operation and a continuous one and is particularly advantageous for tapping packages containing malt liquors or other liquors charged 65 with carbonic acid gas or the like.

It will be noted that various changes may be made in the details of construction without departing from the general spirit of my invention as claimed. 70

Having thus fully described my invention, what I claim as new, and desire to secure by Letters Patent, is—

In combination with a spigot, an upwardly-extending flange, substantially triangular 75 made integral with the forward end of said spigot, the sides of said flange being flat, the edges of said sides being at right angles to one another, the third side of said flange conforming in shape to and made integral with the 80 forward end of said spigot, the said flange having an aperture formed in its forward upper end, a removable handle adapted to engage the said aperture, and an auger secured to the rear end of said spigot, substantially as 85 described.

In testimony whereof I affix my signature in the presence of two witnesses.

BENJAMIN F. ANTILL.
